UNITED STATES PATENT OFFICE.

AUGUSTE L. SALTZMAN, OF EAST ORANGE, NEW JERSEY, ASSIGNOR TO THOMAS A. EDISON, INCORPORATED, OF WEST ORANGE, NEW JERSEY, A CORPORATION OF NEW JERSEY.

TAKE-UP DEVICE FOR MOTION-PICTURE MACHINES.

1,071,800.

Specification of Letters Patent.

Patented Sept. 2, 1913.

Application filed August 17, 1911. Serial No. 644,682.

To all whom it may concern:

Be it known that I, AUGUSTE L. SALTZMAN, a citizen of the United States, residing at East Orange, in the county of Essex, State of New Jersey, have invented certain new and useful Improvements in Take-Up Devices for Motion-Picture Machines; and I declare the following to be a full, true, and exact description of said invention, such as will enable others skilled in the art to which it appertains to make use of the same.

This invention relates to that class of motion picture machines in which a roll of film is unrolled, passed through the machine, and then rolled up again. For this last purpose it is usual to provide a take-up device consisting of a shaft, and a driving means, usually a leather belt, to operate it from the projecting mechanism. If the take-up mechanism does not operate properly, either the strain produced on the film becomes sufficiently great to break it, or it is not wound up at all. It is desirable, therefore, to provide a mechanism which will be very certain and positive in its action and yet simple in construction, and this is one of the objects of my invention.

In motion picture projecting machines, it is desirable that the reel on which the film is wound up may be located directly beneath the machine or in front of it, as the lack of floor space or the convenience of the operator dictates.

Another of the objects of my invention is to provide positive driving mechanism arranged to permit the placing of the take-up reel in either of these two places without any change in the driving mechanism.

In some forms of motion picture projecting machines, such as I have illustrated, the operating mechanism is raised or lowered in order to frame the picture properly before the projecting lens. When the take-up reel is located below the mechanism, this causes the driving center to rise and fall with reference to the take-up reel. When a belt drive for the take-up reel is used, it is a very simple matter to arrange a weighted idler to keep the belt in proper tension, but when a positive driving mechanism, such as a chain belt, which I preferably use, is provided, a weighted idler does not give satisfactory results, nor indeed is it necessary since a positive driving mechanism is not

dependent on friction for its driving power, 55 as is an ordinary belt.

Another of the objects of my invention is to provide a simple form of positive driving mechanism for the take-up reel, which will not be affected by the raising and lowering of the projecting mechanisms.

With these and other objects in view, my invention consists of certain novel features of construction, combination, and arrangement of parts as will be more fully described and pointed out in the appended claims.

Figure 1 is a side elevation of a motion picture projecting machine, the upper portion of which is shown more or less diagrammatically. In this figure, the take-up reel is shown in full lines in position beneath the mechanism, and in front of the mechanism, in dotted lines. Fig. 2 is a side elevation of a portion of the mechanism showing particularly my improved driving devices with the take-up reel in front of the mechanism. Fig. 3 is a plan view of Fig. 2.

The corresponding parts are referred to both in the drawings and in the following 80 description by similar reference characters.

In the accompanying drawings 11 represents a bed plate on which the projecting machine mechanism 12 is mounted.

13 is the upper reel on which the film is 85 mounted before passing it downwardly across the projecting lens of the mechanism 12 to the take-up reel 14.

15 is the framing handle by which the mechanism, including the shaft 16, is raised 90 and lowered, to frame the picture properly before the projecting lens.

17 is a bracket, which may be attached in either of the two positions shown in Fig. 1, either to a portion of the mechanism 12, 95 or to the support 11, as may be desired. This bracket 17 has journaled therein a shaft 18 provided with a key to drive the reel 14 mounted thereon, and a holding device 19 to keep the reel from moving off the shaft 18. The end opposite the reel 14 is provided with the usual friction device 20, consisting of two friction members, one fastened to the shaft 18 and the other free to turn thereon, the two parts being held 105 in frictional contact by the adjustable spring 21.

I provide the loose member of the fric-

tion device 20 with a gear 22 which meshes with a gear 23, mounted on a stud in a bracket 24, loosely mounted on an extension of bracket 17. The bracket 24 permits a planetary motion of the gear 23 about the gear 22, at the same time keeping the gears properly in mesh.

25 is a flat rod attached loosely to the bracket 24, and to a screw 25', the latter being attached to a fixed member 26 of the mechanism 12.

27 and 28 are a pair of chain sprockets, 27 being attached to the driving shaft 16, and 28 to the gear 23, and 29 is the chain transmitting power from 27 to 28. The effective length of the rod 25 is preferably adjustable in any suitable manner as by a slotted connection 25² to compensate for wear or stretching of the chain.

20 When the take-up reel is in front of the projecting mechanism, as shown in Figs. 2 and 3, and in dotted lines in Fig. 1, the reel and its driving mechanism move up and down with the projecting mechanism, as 25 a whole, since the bracket 17 is attached to the projecting mechanism. The rod 25 maintains the sprockets 27 and 28 at a fixed center distance, so that the tension on the chain 29 is constant, and it is obvious that 30 the power of the driving shaft 16 is transmitted through the chain and the gear 23 to the gear 22, and through the friction device 20 to the shaft 18, thus winding up the film as it is passed through the mechanism 12.

40 When the take-up reel is placed below the projecting mechanism, as shown in full lines of Fig. 1, the shaft 18 of the reel is fixed in space, whereas the driving shaft 16 may be moved up and down. When so moved, the rod 25 carries the gear 23 up and down with the mechanism 12, maintaining a fixed distance between the centers of the sprockets 27 and 28, and yet, by reason of the 45 mounting of the gear 23 on the bracket 24, these gears are always properly in mesh.

For convenience of manufacture, I have provided two centers 30 and 31 by which the rod 25 may be attached to the mechanism 12, according to the position of the take-up reel. It is obvious that this rod could be mounted on the hub of the driving shaft 16 in a manner similar to that in which it is attached to the bracket 24.

55 While I have shown a chain and sprocket drive as my preferred form of positive driving means between the driving shaft and take-up reel, I do not limit myself to such form of drive, for, by mounting the gear 23 so as to have a planetary motion about gear 22, I am able to use, between the driving shaft 16 and the gear 22, any form of positive driving means requiring fixed center distances. For instance, a series of spur gears between the driving center and the

gear 23, or a pair of helical gears at the driving shaft, transmitting power through a shaft parallel to the chain 29 to another pair of helical gears at the gear 23, might be used.

Having now described my invention, what I claim as new and desire to secure by Letters Patent is as follows:

1. In a machine of the class described, a film reel shaft mounted in a fixed position, a driving shaft movable toward and away from said film reel shaft, a pair of rotatable members one of which is fixed to said driving shaft and the other of which is operatively connected to said reel shaft, means for maintaining the last named rotatable member spaced at a constant distance from said reel shaft, and means for transmitting power between said rotatable members, substantially as described.

2. In a machine of the class described, a film reel shaft mounted in a fixed position, a driving shaft movable toward and away from said film reel shaft, a pair of chain sprockets one of which is fixed to said driving shaft and the other of which is operatively connected to said reel shaft, means for maintaining said last named sprocket spaced at a constant distance from said reel shaft, and a chain for transmitting power between said sprockets, substantially as described.

3. In a machine of the class described, a film reel shaft, mounted in a fixed position, a driving shaft adapted to be moved toward and away from said film reel shaft, means comprising a chain belt and a pair of chain sprockets adapted to transmit power from the driving shaft to the film reel shaft, and means adapted to maintain one of said sprockets at a fixed distance from the film reel shaft and to keep a uniform tension on said chain regardless of the relative positions of the driving shaft and the film reel shaft, substantially as described.

4. In a machine of the class described, a film reel shaft, a driving shaft, a bracket for supporting the film reel shaft adapted to be fastened in either of two positions to locate the film reel shaft either in front of or beneath the driving shaft, and a positive driving means adapted and arranged to transmit power from the driving shaft to the film reel shaft in either of its two positions, substantially as described.

5. In a machine of the class described, a film reel shaft, a gear on said shaft, a second gear meshing with the first named gear, a bracket supporting said second gear and adapted to permit a planetary motion of said second gear around said first gear, a driving shaft, and a positive driving means between said driving shaft and said second gear, substantially as described.

6. In a machine of the class described, a film reel shaft, a gear on said shaft, a sec-

ond gear meshing with the first named gear, a bracket supporting said second gear and adapted to permit a planetary motion of said second gear around said first gear, a driving shaft, and a chain and gear connection between said driving shaft and said second gear, substantially as described.

7. In a machine of the class described, a film reel, a shaft on which the film reel is mounted, a gear on said shaft, a second gear meshing with the first named gear, a bracket supporting said second gear and adapted to permit a planetary motion of said second gear around said first gear, a driving shaft, a chain and gear connection between the said driving shaft and said second gear, and a bar to hold said second gear at a fixed distance from the driving shaft, substantially as described.

8. In a machine of the class described, a film reel, a shaft on which the film reel is mounted, a gear on said shaft, a second gear meshing with the first named gear, a bracket supporting said second gear and adapted to permit a planetary motion of said second gear around said first gear, a driving shaft, a chain and gear connection between the said driving shaft and said second gear, and a bar of adjustable effective length to hold said second gear at a fixed distance from the driving shaft, substantially as described.

9. In a machine of the class described, a film reel shaft mounted in a fixed position,

a driving shaft adapted to be moved toward and away from said film reel shaft, means for transmitting power from the driving shaft to the film reel shaft comprising a rotatable member, and means for supporting said rotatable member and maintaining the distances between the driving shaft and rotatable member and between the rotatable member and film reel shaft constant regardless of the relative positions of the driving shaft and film reel shaft, substantially as described.

10. In a machine of the class described, a film reel shaft mounted in a fixed position, a driving shaft adapted to be moved toward and away from said film reel shaft, means for transmitting power from the driving shaft to the film reel shaft comprising a gear, and means for mounting said gear for pivotal movement about said film reel shaft and maintaining the distances between the driving shaft and gear and between the gear and film reel shaft constant regardless of the relative positions of the driving shaft and film reel shaft, substantially as described.

This specification signed and witnessed ⁶⁰
this 11th day of August, 1911.
